UNITED STATES PATENT OFFICE.

JULIUS H. WITTEKIND, OF BOSTON, MASSACHUSETTS.

BOTTLE-CLOSURE.

SPECIFICATION forming part of Letters Patent No. 599,886, dated March 1, 1898.

Application filed February 1, 1897. Serial No. 621,420. (No model.)

To all whom it may concern.

Be it known that I, JULIUS H. WITTEKIND, of Boston, in the county of Suffolk and State of Massachusetts, have invented an Improvement in Bottle-Closures, of which the following description, in connection with the accompanying drawings, is a specification, like letters on the drawings representing like parts.

My invention relates to that class of bottle-closures particularly adapted to stop the bottle so as to permit the contents of the bottle to be readily poured out, but to prevent its refilling, the object of my invention being to make a superior stopper and at low cost of manufacture and to make it feasible to produce a stopper of this kind made entirely of glass.

Heretofore there have been many stoppers proposed to be made of glass, but all that I am familiar with have been found to be exceedingly expensive or impossible when the practical making of them in glass has been undertaken. The glass has to be cast in molds, and while in theory the possible shapes and constructions may be almost unlimited they prove in practice to be very limited, and it results that when the many proposed stoppers reach the hands of the practical glass-worker they prove to be impossible without unwarranted expense in making and manipulating the molds and glass, which of course renders the reputed inventions impractical and useless for their intended purposes.

After extended practical experience I have produced the herein-described invention, which is cheap to manufacture, practical in all respects, and accomplishes the objects had in view, particularly in permitting the ready outflow of the liquid and in absolutely preventing any refilling of the bottle.

A further feature of my invention relates to the prevention of removal of the stopper, and consists in interposing an explosive which upon movement of the stopper or entrance of moisture thereto will explode and shatter the bottle-neck, thereby effectually preventing any fraudulent refilling of the bottle in its original appearance.

In the accompanying drawings, illustrative of the preferred embodiment of my invention, Figure 1 is a central vertical section of my improved bottle-stopper in operative position.

Fig. 2 is a horizontal section on line 22, Fig. 1, the valve being omitted. Fig. 3 is a similar sectional view showing a modification. 55 Figs. 4 and 5 are perspective views of the upper and lower portions, respectively, of the casing or shell. Figs. 6 to 10 are perspective views of the separable internal parts and valves of the stopper. Figs. 11 and 12 are 60 similar views of different forms of the retaining-spring.

The casing or shell of the stopper consists of two portions separably connected to permit of the introduction therein of the contained 65 parts, said portions being shown as a crown or cap A and base B, screwed together at b, the latter being a separate piece, as shown in Figs. 1 and 5, or formed integrally with the bottle C, as shown in Fig. 3.

The cap A has its closed or headed top perforated to provide a circle of apertures a and a central obstruction a' and is in the form of a cylinder from one end to the other, with the exceptions of the top flange a², retaining-groove a³, and internal shoulder a⁴, provided for purposes presently described.

The base B has its closed or headed lower end centrally perforated to provide a conical valve-seat b' and contains a number of vertical ribs b², which accurately direct and center the valve D, the latter having its walls vertical excepting at its seating end d, where it is ground to tightly fit its seat b'.

Next to the top a' I provide an annular obstruction E to rest against the shoulder a⁴, said annulus being centrally perforated at e out of alignment with the apertures a and hollowed out on its under side, as at e', to facilitate the flow of the liquid.

Below the annulus E is a stop-diaphragm F, Fig. 7, resting against the lower surface of said annulus and having a central solid portion f, larger than the opening e, from which depend several lugs f' and radial rests 95 or arms f².

The remaining portion of the cap A below the diaphragm F is occupied by a cylindrical block G, Fig. 8, having a central tapered valve-seat g to receive a float-valve H, the block being cut away above the line of seating engagement of the valve therewith to provide ways g' for the ready passage of the liquid. At its lower end the block G is preferably concaved,

as indicated at g^2 , and has an undercut or lip g^3 (see Fig. 1) to retain a spring S, so as to make it easy to assemble the parts and get the spring in correct position.

5 The spring S is spiral and rests within the valve D over a guide-post d' , although the latter may be omitted, if desired, as shown in Fig. 9. In fact, the spring itself may be omitted, if preferred, and this will be desirable in bottling acids or other goods which would attack and eat away metal.

The lower end of the valve D is heavy to facilitate the perfect seating thereof.

15 The internal walls of the portions A and B and the ribs b^2 are made slightly tapering or conical, with their shorter diameters at their closed ends to permit the molding-tools to be simple and to be easily withdrawn from the casting or molded product.

20 All the parts as above mentioned excepting the spring are made readily and practically of glass and in very simple inexpensive molds. They may of course be made of any other substance, if preferred; but one principal purpose of my invention is to devise a stopper of such parts and of parts having such shape, relations, and practical construction that it may be made cheaply and entirely of glass.

25 30 The parts are assembled by inverting the portion A, dropping the annulus E against the shoulder a^4 , placing the stop F thereon, depositing the ball-valve H on the lugs f' , and inserting the block G, the spring S, when used, being snapped into the holding-groove g^3 . The bottom edge of block G will then come flush with the adjacent end of the cap portion A. A washer a^5 is then placed over the said flush edges, the valve D is turned 35 over its spring S, the base B screwed down into place, and the completely-assembled stopper is inverted into proper upright position ready for insertion into the bottle-neck.

In order to aid in retaining the stopper and 40 also for another purpose presently described, I insert in the groove a^3 a spring-keeper K, Fig. 11, or K', Fig. 12, which fits back snugly into the recess and has resilient tongues k k' projecting therefrom to engage a registering 45 recess m in the bottle.

The spring-keeper K has a rectangular or 50 enlarged bottom edge k^2 , so that when the tongues k are pressed in together by the insertion of the stopper into the neck of the 55 bottle there is yet remaining an appreciable pocket between the then parallel front and rear portions of the keeper K before the former have snapped out into the recess m , Fig. 1, and this space or pocket I fill with an 60 explosive or fulminate k^3 , preferably held by a wrapper k^4 of skin, oiled paper, or other substance. Similarly a pocket is formed in the spring K' by the lapping over of the tongues k' , the pocket being triangular instead of rectangular, as in Fig. 1, and this 65 pocket will be filled with like explosive k^3 .

If then, the parts being placed as shown in Fig. 1, any one should attempt to forcibly withdraw the stopper, the arms k or k' , as the case might be, would be buckled forcibly 70 against the explosive, and the latter would thereby be exploded with sufficient force to shatter the neck of the bottle.

Preferably the stopper will be cemented into the bottle-neck, and in such case I propose to employ as the explosive fulminate of mercury, so that if an acid should be used to cut out the cement it would explode the charge k^3 immediately upon reaching it.

Cork or other packing-washers m m^2 are 80 employed to prevent any accidental access of moisture to the explosive.

It will be evident without further extended explanation that as the bottle is tipped or inverted to pour out its contents the liquid 85 will readily flow through the perforated base around the valve D, into the recess g^2 , and through the openings g and g' , around the stop f , thence into the cavity e' , through the perforation e into the adjacent chamber, and 90 finally out through the apertures a .

If any attempt should be made to refill the bottle, the latter being in an upright position, it will be found to be impossible, because the heavy valve D will positively close the stopper, and if the bottle is immersed in an inverted position the float-valve H would rise and effectually close the stopper.

The valve H will be made of cork coated with paraffin or other wax not readily attacked 100 by the liquor or other contents of the bottle.

A usual cork N will be inserted over the stopper to seal the bottle for shipping purposes.

I am aware that it has been heretofore proposed to provide ear-doors with percussion-alarms giving audible notice of the surreptitious opening of the door, and I therefore disclaim anything of that sort, my invention consisting of an explosive in a bottle so placed 105 between the stopper and the bottle-neck that it will explode and shatter the neck of the bottle whenever it is attempted to remove the stopper, the shattering of the bottle-neck being the object in view irrespective of whether 110 any alarm is given or not.

Having fully described my invention, what I claim, and desire to secure by Letters Patent, is—

1. A bottle-stopper, comprising a cap and 120 a base, having their opposite headed ends perforated, the latter to constitute a central valve-seat and the former to constitute an annular series of openings with a closed center, said cap having an internal shoulder 125 slightly removed from its head, an annular piece resting on said shoulder, concave on its under side and having a central opening out of register with said series of openings, a stop-piece engaging said annular piece and having 130 a central stop larger than the said central opening, a cylindrical block having a central

tapered valve-seat, a float-valve therein, and a gravity-valve in said base, substantially as described.

2. A bottle-stopper, comprising a cap having an external flange a^2 , a perforated outer end, an internal shoulder adjacent thereto, a cylindrical exterior, and a slightly-tapering or conical interior; an annular piece, a stop, and a valve-block, resting successively against each other and occupying the space between said shoulder and the inner end of said cap, said block having a tapering valve seat and passage, a float-valve therein, the lower end of said block having an undercut portion to retain a spring, a spring therefor, a lower valve-seat, and a valve therefor, said valve being engaged by said spring, substantially as described.

3. The combination with a bottle-stopper and a bottle within which said stopper is placed, of a pocket between the stopper and the bottle-neck, and an explosive therein capable of shattering the neck when exploded, substantially as and for the purpose described.

4. The combination with a bottle-stopper, of a pocket, an explosive therein, and a spring adjacent and to act upon the explosive and engaging the bottle, removal of the stopper causing said spring to explode said explosive, substantially as described.

5. The combination with a bottle-stopper and a bottle-neck, provided with registering

recesses, of a spring fitting snugly in one of said recesses and having a resilient tongue 35 extending into the other recess, and an explosive in said recesses to be exploded by the action of said spring upon attempted removal of the stopper, substantially as described.

6. The combination with a bottle, of a bottle-stopper, comprising a cap having an external flange a^2 , and a perforated outer end, said flange being adapted to rest on an internal shoulder provided in the bottle-neck, a washer being pressed between and by said 45 flange and shoulder, an annular piece, a stop, and a valve-block, resting successively next to each other within said cap, and a valve within said block operating between the same and said stop, the lower end of said block being flush with the lower end of said cap, a base containing a valve and a valve-seat at its lower end, and at its upper end abutting the lower end of said cap, a washer on top of said base covering the joint between said 50 block and cap, and a washer at the lower end of said base between the latter and the bottle-neck, substantially as described.

In testimony whereof I have signed my name to this specification in the presence of 60 two subscribing witnesses.

JULIUS H. WITTEKIND.
